(57) **CLAIM**

The ornamental design for a watch, as shown and described.

DESCRIPTION

FIG. 1 is a front perspective view of a watch according to my
new design;

FIG. 2 is a front elevation view of the watch;

FIG. 3 is a right side elevation view, the left side being a
mirror image thereof;

FIG. 4 is a top plan view, the bottom plan being a mirror
image thereof; and,

FIG. 5 is a rear elevation view.

The broken line showings of FIGS. 1-2 are for illustrative
purposes only and form no part of the claimed design.
